PROCESS OF MAKING A HEAT EXCHANGING ELEMENT

Alfred J. Berg, Portsmouth, N. H., and John O. Huse, United States Navy

Application August 4, 1937, Serial No. 157,380

2 Claims. (Cl. 29—157.3)

(Granted under the act of March 3, 1883, as amended April 30, 1928; 370 O. G. 757)

The usual heat exchanging element comprises a tube or other hollow or solid body having one or more ribs projecting from the exterior surface thereof. The body or its content is usually at one temperature while the fluid in contact with the exterior surface of the body and ribs is at a different temperature and exchange takes place between them through the medium of the ribs and the body. Heretofore, such ribs have been attached to such bodies in various ways which present numerous difficulties and problems in construction, including expensive production, weakening of the wall of the body or of the rib, either or both, difficulty in maintaining the rib from flexure or deformation, among other problems with which those skilled in the art are familiar.

Our present invention overcomes such difficulties and problems in an inexpensive and durable manner resulting in a product that is neat and well finished as well as of great efficiency in its heat exchanging capacity and of substantially lesser weight and cost without detracting from the strength of the resulting product, or the impairment of its resistance to corrosion or other injurious action of the elements.

Our product and method is illustrated in the accompanying drawing in which Fig. 1 is a side elevation view of a strip of metal which is to be converted into a heat exchanger rib or ribs together with a side elevation view of the apparatus for practicing our method of forming the inner edge of such rib which is to contact with the outer surface of the heat exchanging element or body;

Fig. 1a is an enlarged central vertical sectional view of a portion of the outer edge of the knurling wheel shown in Fig. 1;

Fig. 2 is a perspective view of a short broken-off portion of the flat straight rib forming strip after the same has been helically formed about, and for clarity removed from, the heat exchanger element or body;

Fig. 3 is a plan view of a broken-away portion of a helically ribbed heat exchanger element or body in which the rib supporting and heat transfer bond increasing feet are partially formed;

Fig. 3a is an end view of a portion of the structure shown in Fig. 3;

Fig. 4 is a view similar to Fig. 3 but showing the rib supporting and heat transfer bond increasing feet in a more finished form;

Fig. 4a is an end view, similar to Fig. 3a, of an end view of a portion of the structure shown in Fig. 4;

Fig. 5 is a view; similar to Fig. 4 but, showing the rib supporting and heat transfer bond increasing feet in their finished form;

Fig. 5a is an end view similar to Fig. 4a, of the structure shown in Fig. 5.

In the drawing, in which like characters of reference indicate the same parts, 10 represents the rib material which is in the form of a flat strip of metal of the thickness and width and character of metal desired. This strip 10 is first run edgewise between a stationary support 11 and a rotatable wheel 12. The support 11 is provided with a groove in its side adjacent wheel 12, in which groove the strip 10 is supported upon one of its edges as well as upon its opposite sides by said groove; said groove being wide enough to freely receive the strip 10 and of a depth such that the opposite edge of strip 10 extends but slightly from the adjacent surfaces of the support 11. The wheel 12 is provided on its periphery with a plurality of knurling teeth 13 which engage the exposed edge of the strip 10 which projects beyond the depth of the notch in support 11 in which the strip 10 slides. The lateral walls of this notch insure the strip being held in upright engagement with the tooth periphery of the wheel 12, while the bottom of said notch in support 11 maintains strip 10 in its desired engagement with the toothed periphery of wheel 12. When the end of a strip 10 is inserted into the groove in support 11 and wheel 12 is rotated manually or by power, the teeth 13 on the periphery of wheel 12 will form alternate projections 14 and intervening spaces 15 in the edge of strip 11 in engagement with the notched periphery of wheel 12. In such knurling the metal of strip 11, that was formerly in the spaces 15, will be cold worked by the knurling teeth 13 into and increase the height of the adjacent projections 14.

The width of the groove in support 11 which receives the strip 10 may be adjustable to accommodate different thicknesses that may be desired for the metal of the strip 10, while the bottom of said groove in support 11, which bears against one edge of strip 10 and the periphery of wheel 12 may be relatively adjusted to accommodate different desired widths of strips 10. Said adjustments may be made by the plurality of bolts 16 in the support 11, or otherwise as may be desired.

Preferably secured to support 11, and to the side of wheel 12 opposite that from which the strip 10 is to be moved into engagement with wheel 12, is a foot 17 which is provided with a cam surface 18 which terminates adjacent wheel 12 with a bevelled surface 19. These surfaces 55

18 and 19 merge into each other and are adapted to engage and blunt or flatten the peaks of projections 14 formed upon an edge of strip 10 as aforesaid, the thrust of said flattening being 5 borne by the support 11 and its foot 17 which is attached thereto by a suitable shank or otherwise.

As the strip comes from the successive and continuing knurling and flattening operations, 10 the flattened surface adjacent its end is associated with and secured by solder or otherwise to the outer surface of a tubular or other shaped body 20 which may be hollow, said association preferably being with an initial portion of the 15 edge of strip 10, after the same has been knurled, and the knurled projections 14 flattened at least in part, engaging an outer surface of the tube or body 20, with the sides of strip 10 extending at an angle, which may be a right angle, from 20 the tube or body 20.

The strip 10 is then progressively bent edge-wise about, or otherwise, into conformation with the surface of the tube or body 20. This edge-wise bending progresses from said initial securing, 25 and preferably extends throughout the length of the association of the strip 10 with the surface of the tube or body 20. Such pressure is preferably progressively and successively applied throughout the length of the strip 10 30 being conformed into continuous engagement with the surface of the tube or body 20. Such successive pressure applications not only conform by stages the cold worked edge of the strip 10 to the surface of tube or body 20, but also 35 progressively further flatten the adjacent surface of projections 21 into contact with the surface of the tube or body 20.

The strip 10, for greater strength, as well as 40 heat exchanger efficiency, is preferably cold rolled or otherwise cold worked. This cold working increases the strength of the strip 10 as well as its heat exchanging capacity or efficiency. This enables the strips 10 to be employed of 45 much thinner as well as wider metal than has been heretofore found possible as well as practicable. The thinner the strips 10, and within limits the wider they are, the greater the increase in lightness as well as the heat exchanger capacity or efficiency of the tube or body 20 50 provided with the strips 10 in the form of a rib or ribs extending from the surface of the tube or body 20, and also the greater the reduction in the cost of the resulting product. This is true because the thinner the strips are the 55 lesser will be the weight and cost of the resulting product. The thinner and wider are said strips 10 the larger is the area of their external surfaces compared to the cross-section of the metal of the strips 10. Furthermore, the thinner and wider are such strips 10 the greater is 60 the number of such strips that may be placed upon or about the surface of a given length and diameter of tube or body 20 with the required, preferably uniform, space between the strips 10 65 on the finished product.

A further economy in weight and cost, without impairment of its strength and efficiency, is the fact that the surface of the tube or body 20 is the virgin metal of which the tube or body 70 20 is formed without thinning such wall or otherwise impairing its strength and efficiency.

When the strip 10 is bent and conformed helically about and to the surface of the tube or body 20, all of the operations hereinbefore stated 75 are preferably performed progressively through-

out the whole length or desired length of the tube or body 20; and such operations preferably are in successive stages until the desired conformation of the inner edge of the strip 10 and the outer surface of its flattened projections 14, 5 21, are of the desired conformation with the surface of the tube or body 20.

When the strip 10 is formed in a plurality of rings about the tube or body 20 the meeting ends of the strip 10 are severed or may be permitted to slightly overlap.

When the strip or strips 10 surround the tube or body 20 either in a ring or by helical convolutions, it will ordinarily be necessary only to solder or otherwise secure such strip to tube or 15 body 20 only at or adjacent their opposite ends because the inner edge of the strip or strips 10 is continuously in firm engagement with the surface of the tube or body 20.

Further advantages arising from said construction are that the cold working of the edge of the strip or strips 10 adapted to engage the surface of the tube or body 10 increases the thermal conductivity between the tube or body 20 and the strip 10; also that the feet or lateral 20 projections 21 of the strip or strips 10 increase not only the thermal conductivity between the tube or body 20 and each strip 10 but also substantially increase the rigidity of each strip 10 25 as well as its stability and resistance to deformation as well as lateral bending relative to the tube or body 20. This increased stability and resistance to deformation or lateral bending is of great advantage due to the fact that if the spaces between the strips 10 forming ribs 30 or fins 10a upon the finished product be un-uniformly spaced apart or laterally bent into contact with each other, the heat exchanging efficiency of the product is proportionately impaired, 35 besides rendering the finished product un-uniform and/or unpleasing in appearance. The accomplishment of these objects even with thinner, lighter, and to such extent cheaper material for the strips 10, lends greater importance 40 to the means by which such objects are accomplished because otherwise the thinner, wider strips 10 in the finished product would be more liable 45 to distortion and lateral bending even with ordinary handling. Furthermore, the increased lateral support for the high standing ribs or fins 50 formed of the strip or strips 10 as well as the greater heat exchanging contact of such ribs or fins 10a with the tube or body 20, afforded by the projections 21 extending alternately from 55 opposite sides, does not impair appreciably the volume of the heat exchanger space between the ribs or fins.

The preferred construction and arrangement of the teeth 13 of wheel 12, with their function, will now be described. A plurality of adjacent 60 teeth 14 have their outer surfaces beveled, as shown in Fig. 1a. The individual teeth 13 are spaced apart by bevelled notches. These notches are of uniform diameter at their bottoms while the ridges of the teeth 13 between the notches 65 have their outer surfaces bevelled and uniformly sharp throughout the extent of the bevel. This beveling of the peripheries of the teeth 13 affords a steeper slope of the valleys between the high points of the teeth 13 and progressively 70 blunter slopes as the teeth 13 approach their opposite sides. These bevelled teeth 13 are in series of two or more teeth which are bevelled in one direction while the joining series of teeth 13 are bevelled in the opposite direction. These 75

teeth 13 thus alternate in the direction of their bevels throughout the periphery of wheel 12. When such bevelled teeth 13 engage the edge of strip 10 projecting from the holder 11 the strip 10 will be drawn through the groove in holder 11 by the rotation of wheel 12 and the embedment of teeth 13 in the adjacent edge of strip 10. This embedding of the bevelled teeth 13 into the edge of strip 10 causes alternating series 10 of oppositely bevelled notches to be formed in the adjacent edge of strip 10. In the formation of such notches the metal of strip 10 between such notches is displaced laterally of the normal thickness of the strip 10 in a direction away from the high points of the series of teeth 13 of wheel 12 which formed the notches in the edge of strip 10. This results in alternate projections upon opposite sides of the strip 13 which ultimately become the feet 21.

As the thus formed notches 15 in the edge of strip 10 emerge from wheel 12 they are progressively engaged, and substantially flattened by the surfaces 19, 18, of the foot 17. This engagement also tends to increase the extent of alternate lateral projection from the sides of strip 10 of the projections 14. From support 11, wheel 10 and foot 17, the strip 10 progresses to the point where the flat strip 10 (one of whose edges has been cold worked as heretofore stated) is bent edgewise about the tube or heat exchanger element 20 with said cold worked edge of strip 10 in contact with the outer surface of tube or element 20. In the course of the helical bending of strip 10 about the tube or element 20 the initial lateral projections formed upon an edge of strip 10 by the wheel 12 and foot 17 heretofore described are progressively transformed into lateral projecting feet 21 on opposite sides of the inner edge of the helically coiled rib or fin. Such feet 21 are formed in progressive stages illustrated in the order of their progression in Figs. 3, 3a, 4, 4a, and 5, 5a, a portion of the rib or fin 10a in an intermediate one of said stages being shown in Fig. 2 from which the tube or element 20 has been removed in order to more clearly illustrate a portion of the interior of the coiled rib or fin.

In so associating the strip 10 and the tube or element 20 and their conversion into the finished product the virgin surface of the metal of the tube or element 20 is not disturbed and the strip 10 is desirably bent thereabout and the feet 5 21 formed in firm binding contact with the normal surface of the tube or element 20 without requiring any thinning or other disturbance of the wall of the tube or element 20 in the securing of the rib or fin, strip 10, and its integral 10 feet 21 to and about the tube or element 20 in firm and highly efficient heat exchanging contact.

This invention may be made and used by or for the Government of the United States for governmental purposes without the payment of any royalty thereon or therefor.

Having now so fully described our invention that others may therefrom make and use the same, what we claim is:

1. The method of cold working the edge of a strip of metal adapted to contact with a heat exchanger element, comprising forming alternate projections and depressions in said edge of said strip by flowing metal of said edge from the area 25 of the depressions into the area of the adjacent projections and flattening at least the peaks of said projections by lateral displacement of the metal from said peaks into alternate projections from opposite sides of the strip.

2. The method of fabricating a heat exchange device including a member having mounted thereon a strip of metal, comprising the steps of forming alternate projections and depressions in the edge of said strip adapted to contact said member by flowing metal of said edge from the area of the depressions into the area of the adjacent projections, flattening at least the peaks of said projections by lateral displacement of the metal from said peaks into alternate projections 40 from opposite sides of the strip and conforming the aforesaid edge with the lateral projections to the outer surface of said member whereby to provide a firm and efficient heat exchange contact therebetween.

JOHN O. HUSE.
